DESIGN FOR A BALANCE

Harry Bennett, New York, N. Y.

Application February 1, 1936, Serial No. 60,943

Term of patent 7 years

To all whom it may concern:

Be it known that I, Harry Bennett, a citizen of the United States, residing in New York, in the county of New York and State of New York, have invented a new, original, and ornamental Design for a Balance, of which the following is a specification, reference being had to the accompanying drawing, forming part thereof, and which is a perspective view of a balance, showing my new design.

I claim:

The ornamental design for a balance, as shown.

HARRY BENNETT.
